UNITED STATES PATENT OFFICE.

HERBERT C. DRUMM, OF CANTON, OHIO, ASSIGNOR TO THE UNION METAL MANUFACTURING COMPANY, OF CANTON, OHIO, A CORPORATION OF OHIO.

LANTERN.

Application filed December 18, 1919. Serial No. 345,783.

To all whom it may concern:

Be it known that I, HERBERT C. DRUMM, a citizen of the United States, residing at Canton, in the county of Stark and State of Ohio, have invented a new and useful Lantern, of which the following is a specification.

This invention relates to improvements in lanterns and more especially to the construction of the frame work of lanterns such as are ordinarily used for street lighting.

The objects of this invention are to provide a lantern in which the frame is made up of upper and lower castings secured together by means of strips of base metal covered with sheets of a finer metal; to provide a lantern construction in which a reflector and light are suspended and are readily removable and replaceable; to provide means for easily and readily removing the top or cover of the lantern; to provide means for easy access to the interior of the lantern; to provide simple and efficient means for retaining the glass panels within the frame and to generally simplify and improve the character of lantern mentioned.

With these objects in view the invention consists in the novel construction and arrangement of parts, hereinafter described, illustrated in the accompanying drawings, and particularly pointed out in the appended claim, it being understood that various changes in the form, proportions, size and minor details of construction may be made within the scope of the appended claim, without departing from the spirit or sacrificing any of the advantages of the invention.

The invention thus set forth in general terms is illustrated in the accompanying drawings forming part hereof, in which—

Figure 1 is a perspective view of the lantern, the glass being broken for the purpose of illustration.

Fig. 2 is a vertical sectional view through one-half of the lantern.

Fig. 3 is a fragmentary sectional view of the upper portion of the lantern showing the means for connecting the top or cover.

Fig. 4 is a sectional view through a portion of one of the upright strips of the frame showing the means of connecting the screw studs thereto.

Fig. 5 is a transverse sectional view on the line 5—5, Fig. 2; and

Fig. 6 is a fragmentary sectional view showing the door construction.

A practical embodiment of the invention is disclosed in the accompanying drawings, forming a part of this specification in which similar numerals of reference indicate corresponding parts throughout the several views.

The lantern frame comprises generally the upper ring 1 which is preferably a bronze casting, the lower ring 2, which is also a bronze casting and the upright strips which are connected to both of said castings and space the upper casting above the lower, these strips comprising a strip 3 of galvanized iron or other base metal covered with a thin sheet 4 of copper or other finer metal, the edges of said copper sheet being turned over the inner side of the iron sheet as shown at 5 thus permanently securing the thin outer sheet upon the heavier inner strip.

The lower ring or casting 2 is provided with the integral horizontal lugs 6, screws 7 or their equivalents being located through said lugs and through the base portion 8 of the lantern, which base may be the upper end of a light pole or the like. The lantern is thus securely and detachably mounted upon the base and may be easily and readily secured upon or removed from the base.

The lower ring or casting 2 is provided at intervals with sockets 9 which receive the lower ends of the upright strips, screws 10 or their equivalents being located through the strips and through the casting. The upright strips are connected at their upper ends to the upper ring or casting 1 by means of screws 11 or their equivalents.

For the purpose of supporting an electric lamp and a reflector within the lantern, brackets or angles 12 are connected to alternate strips 3 and to the upper ring or casting 1 by means of screws 13, an annular reflector 14 preferably formed of porcelain or the like being supported upon said brackets.

An inverted U-shaped supporting bracket 16 is connected at its lower end to the reflector by means of bolts 17 or the like and supports a lamp socket 18 of any usual and well known construction which contains an incandescent lamp 19 or the like protruding through the open center of the reflector 14.

For the purpose of retaining the glass panels 20 within the frame of the lantern,

metal strips 21 are provided upon the interior of the lantern, one of these strips being located upon the inner side of adjacent edges of the glass panels at each of the upright strips. The iron strips 3 are provided at intervals with inwardly disposed frusto-conical sockets 22 which receive the head 23 of a bolt 24, these screws being retained within the sockets 25 or the like. The bolts extend 10 inwardly between the edges of adjacent glass panels and through suitable apertures in the strips 21, nuts 26 being provided thereon to draw the strips 21 against the edge portions of the glass panels thus tightly 15 clamping the glass between the strips 3 and 21. It will of course be understood that the bolts 24 are soldered or otherwise permanently connected within the sockets 22.

The cover comprises the lower ring 28 20 which may be formed of sheet metal provided with the horizontally disposed flange 29 and the down turned folded peripheral flange 30 and with the upwardly angularly disposed flange 31; the upper casting 32 25 having the downwardly and angularly disposed flange 33; and with the connecting strips similar to the upright strips 3 and comprising the heavier galvanized iron strips 34 covered with the lighter strips 35 30 formed of bronze or other fine metal, the strips being connected to the flange portion 31 of the lower ring by means of bolts 36 and to the flange portion 33 of the upper casting by means of bolts 37, glass panels 38 35 being interposed between the strips 34 and inner strips 39 through which the bolts 36 and 37 are also located.

For the purpose of connecting the cover to the lantern, lugs 40 downwardly depending from the cover are connected to the ring 28 of the cover as by means of rivets 41, these lugs being provided with threaded apertures 42 which receive the screws 43 located through the upper casting 1. For the 45 purpose of giving the cover a finished appearance a sheet metal ornament 44 may be connected to the casting 32 by means of a bolt 45.

In order to provide for ready access to the 50 interior of the lantern a door is provided comprising a sheet metal channel frame 46 hingedly connected at its upper end to the casting 1 by means of suitable hinges 47 and provided with a glass panel 48, a screw 49

passing through the lower portion of said channel and arranged to engage a screw threaded aperture 50 in the lower ring 2 for the purpose of retaining the door in closed position.

Attention is called to the fact that the upright strips 3 although formed of sheet metal are so shaped that they have sufficient strength to carry the weight of the upper casting 1 as well as the cover and the reflector and lamp, the entire weight of the lantern being thus supported from the lower casting 2 by means of these strips. By forming the strips of the cross sectional shape best shown in Fig. 5 and covering them with a thin sheet of finer metal sufficient strength is produced to support the weight of the whole structure while at the same time the thin sheets of finer metal give the lamp a finished appearance without the necessity of forming the entire strip of finer metal, thus 75 materially reducing the cost as well as considerably strengthening the construction of the finished structure. In the past it has been common to form structures of this character either entirely from castings or else to 80 form the upper and lower rings of sheet metal but with the present construction by forming the strips of the cross sectional shape shown and in the manner described a 85 very strong structure is produced in which very thin sheet metal can be employed for covering the strips.

This lantern is so designed and constructed that it may be used either upon the upper end of a pillar or column as shown or it 90 may be supported from its upper end in a pendant position without changing the construction of the lantern in any way.

I claim:

A lantern including a frame having upright members and glass panels supported thereon, brackets mounted upon the upper portion of the frame, an annular reflector supported upon the brackets and provided with a central opening, an inverted U-shaped bracket extending upward from said reflector and a lamp depending from said U-shaped bracket and through the central opening in the reflector.

In testimony that I claim the above, I 105 have hereunto subscribed my name.

HERBERT C. DRUMM,
